UNITED STATES PATENT OFFICE.

CHARLES H. GREENWOOD, OF CANTON, OHIO.

BOBBIN WINDER.

Application filed January 26, 1923. Serial No. 615,125.

To all whom it may concern:

Be it known that I, CHARLES H. GREENWOOD, a citizen of the United States, residing at Canton, in the county of Stark and State 5 of Ohio, have invented certain new and useful Improvements in Bobbin Winders, of which the following is a specification.

This invention relates to bobbin winders for sewing machines. There are a great 10 number of objections to the different types of bobbin winders at present in common use. The bobbin being rotatable upon an axis substantially parallel to the longitudinal center of the machine, causes considerable 15 inconvenience to the operator in placing the bobbin in the winder and removing the same therefrom, as well as in threading the bobbin.

Owing to this position of the bobbin 20 winder, it is generally necessary to feed the thread to the bobbin from the front or side of the machine or from above the bobbin, making it necessary either to guide the thread by hand or to provide some means for 25 guiding the thread back and forth upon the bobbin to coil the same evenly thereon. Where automatic devices are used to guide the thread evenly back and forth upon the bobbin, it is necessary to include in the mechanism gears, springs and other delicate parts 30 which are easily bent or broken.

It has been found that such a construction does not always coil the thread evenly upon the bobbin, as the device must be designed 35 for a standard weight of thread which will cause heavier thread to pile up upon the bobbin, while lighter thread would necessarily be wound with the coils spaced from each other.

It is also necessary with such a construction to drive the bobbin winder from the periphery of the hand wheel, and as the same is rounded, the bobbin winder is often caused 40 to slip during the operation thereof.

Considerable annoyance has been caused 45 by bobbin winders of usual construction, as the same take up considerable space upon the outside of the machine, and frequently are accidentally disengaged from the hand wheel 50 during the operation of winding or have no positive means for automatically disengaging from the hand wheel when the bobbin is full.

It has also been found that considerable 55 trouble is caused with bobbin winders of this description, as they are located in such a

position that they protrude outward toward the operator and are then accidentally thrown into engagement with the hand wheel, causing the machine to run hard. 60

The objects of the present invention are to overcome the objections above enumerated by providing a simple and efficient bobbin winder which is almost entirely enclosed and which engages the face of the hand wheel, 65 which should be of disk form for the purposes of this invention.

Another object is to provide means for positively holding the friction driving wheel of the bobbin winder in engagement with 70 the face of the disk hand wheel during the winding operation, and to cause the same to be automatically disengaged from the hand wheel and dropped into inoperative position 75 when the bobbin is filled.

Other objects are to provide a motor drive for engagement with the disk hand wheel having simple and effective means for easily and readily changing the speed of the hand wheel and for starting and stopping the 80 rotation of the same.

A further object of the improvement is to mount the bobbin upon a spindle located substantially transversely to the axis of the hand wheel, in order to permit the same to 85 be easily placed upon or removed from the spindle and to facilitate the threading of the bobbin; and to permit the thread to be fed to the bobbin from the eye of the needle or other suitable point at a considerable distance from the bobbin, causing the thread to wind itself evenly upon the bobbin without the necessity of automatic feeding mechanism. 90

A still further object is to provide a bobbin winder of this type which dispenses with the use of springs, gears and other delicate parts which may be easily bent or broken and to enclose the greater portion of the bobbin winder mechanism in order to protect the same from injury. 95

The above and other objects may be attained by constructing the device in the manner illustrated in the accompanying drawings, in which— 100

Fig. 1 is a top plan view of a sewing machine provided with the improved bobbin winder;

Fig. 2, a side elevation of the same; 110

Fig. 3, an enlarged section on the line

3—3, Fig. 1; and

Fig. 4, a view similar to Fig. 3, showing

the bobbin winder in the inoperative position.

Similar numerals of reference indicate corresponding parts throughout the several figures of the drawings.

The goose-neck 1 and head 2 of the machine may be of any usual and well known construction, and the hand wheel 3 is of disk form, as best shown in Figs. 3 and 4. The hand wheel may be provided with a grooved pulley 4 for the reception of a belt 5 by means of which it may be driven by foot power or an electric motor such as shown at 6, may be provided for driving the hand wheel, a squared shaft 7 being slidably mounted within a similar squared passage in the motor shaft and provided with a friction roller 8 for engagement with the face of the disk wheel 3.

10 A lever 9 is arranged to be operated by the hand, knee or foot of the operator, being operatively connected to the lower end of the squared shaft 7 for the purpose of sliding the shaft vertically to move the friction wheel 8 toward or from the center of the disk hand wheel, in order to increase or decrease the speed of the hand wheel, and to be moved entirely out of engagement with the hand wheel to stop the same.

20 The bobbin winder includes the angular arm 10 pivoted at one end as at 11 to the plate 12, which is preferably provided with the inwardly extended, annular flange 13, forming a housing for the bobbin winder, this flange 13 being cut out as at 14 upon the side toward the hand wheel to permit the arm 10 to oscillate. The plate or housing 12 is connected to the goose-neck of the machine as by the screws 15 or their equivalents.

30 The friction roller 16 is fixed upon the spindle 17 which is journaled upon the outer end of the arm 10, said friction roller being provided with a tire 18 of rubber or other suitable friction material, arranged to be moved into engagement with the face of the disk hand wheel 3, as illustrated in Figs. 1, 2 and 3.

The spindle 17 is preferably hollow and split longitudinally as shown at 18^a, in order to permit the bobbin 19 to be easily placed upon or removed from the spindle. A bell crank 20 is pivoted as at 21 upon the arm 10, the lower arm 22 thereof being provided with a notch 23 arranged to engage the stud 24 fixed upon the plate 12.

The forward arm 25 of said bell crank is provided with a depending flange 26 arranged to be engaged by the thread wound upon the bobbin, as shown in Fig. 3, to tilt the bell crank upon its pivot and release the notched arm 22 thereof from the pin 24, the weight of the arm 10 and the devices threaded thereon causing the same to drop, without the use of springs or similar devices, into the

inoperative position, as shown in Fig. 4, automatically moving the friction wheel 16 out of engagement with the disk hand wheel, when the bobbin is filled.

In winding the bobbin, the same is placed upon the spindle 17 and the arm 10 raised until the notch 23 upon the bell crank engages the stud 24, as shown in Fig. 2. The friction pulley 16 is then held in frictional engagement with the face of the disk hand wheel.

The thread may then be pulled from the spool 27 and pulled through the head and threaded through the needle 28 and extended up to the bobbin, the end of the thread being drawn into the slot 29 in the side wall of the bobbin, instead of tying or winding the thread around the bobbin or threading it through the usual hole in the bobbin. The hand wheel is then rotated, either by foot power or the motor, rotating the bobbin through the disk hand wheel 3 and friction pulley 16, winding the thread upon the bobbin.

It will be seen that if the needle is already threaded for sewing, it is only necessary to pull the loose end of the thread over to the bobbin and draw the same through the slot 29. In threading the device in this manner, the needle bar may be held in the raised position by any suitable means, such as the needle threading device illustrated and described in my copending application upon needle threader. If desired, however, the thread as shown at B in dotted lines, may be passed from the spool through the eyelet C located upon the head of the machine and then to the bobbin.

With this construction, it will be seen that by using two spools of thread instead of one, the bobbin may be wound at the same time the machine is in operation for sewing, as the winding operation is entirely automatic, the thread guiding itself back and forth upon the bobbin and winding evenly thereon and automatically throwing the bobbin winder out of operative engagement with the hand wheel when the bobbin is filled.

It should be noted that as the bobbin winder is almost entirely enclosed within the casing or housing 12 and is located against the goose-neck, it will obviate the possibility of accidentally striking the bobbin winder, and throwing the same into engagement with the hand wheel, which necessarily causes the machine to run harder.

This is a common objection to bobbin winders of usual construction. It will also be seen that the bobbin winder being located in this position, will not be in danger of being accidentally struck and thrown out of operative engagement with the hand wheel during the operation of the same for winding the bobbin.

As the bobbin is threaded upon a spindle

located substantially transversely to the axis of the hand wheel, it will readily be seen that the bobbin may be easily and quickly placed upon or removed from the spindle, 50

as this is the most convenient and natural position for the operator to accomplish the same, and the bobbin may be easily threaded in this position. 55

As the friction pulley upon the bobbin 10 winder engages the flat surface of the disk hand wheel, and is held in frictional engagement therewith by means of the bell crank until the filling of the bobbin releases the same, it will be obvious that the difficulties 15 referred to in connection with the common forms of bobbin winders, which engage the rounded periphery of the hand wheel, are overcome. 60

From the above, it will be obvious that a 20 simple and effective bobbin winder is provided which overcomes the objections common in bobbin winders at present in use, as the bobbin winder mechanism is almost entirely enclosed and is located in a position 25 where it will not be accidentally struck by the operator, thus not only protecting the mechanism from injury, but also preventing the bobbin winder from being accidentally thrown into engagement with the wheel or 30 out of engagement therewith. 65

It will also be seen that this mechanism does away with the necessity of using springs, gears, thread guides and other delicate parts, which may be easily bent or 35 broken or otherwise injured to affect their usefulness. 70

I claim:

1. In combination with a sewing machine 40 having a goose neck and head, a bobbin winder mounted upon the goose neck and provided with a horizontally disposed bobbin spindle located substantially transversely to the goose neck and disposed toward the operator of the machine. 80

2. In combination with a sewing machine, 45 a disk hand wheel thereon and a bobbin 85

winder provided with a friction wheel arranged to engage the face of the disk hand wheel and having a horizontally disposed spindle disposed toward the operator. 50

3. In combination with a sewing machine, a bobbin winder comprising mechanism located within the housing and protruding through the side thereof and a friction wheel carried by said mechanism for engagement with the hand wheel of the sewing machine. 55

4. A bobbin winder including a pivoted arm, a bobbin spindle and friction wheel upon the free extremity of the arm, means 60 for holding the arm in raised position to hold the friction wheel in engagement with the hand wheel of the sewing machine, and means for releasing the arm to permit the same to drop of its own weight into the inoperative position. 65

5. A bobbin winder including a pivoted arm having a bobbin spindle and friction wheel upon the free end thereof, means for holding the arm in the raised position to 70 hold the friction wheel in engagement with the hand wheel of the sewing machine and means automatically operated by the filling of the bobbin to release the arm and permit the same to drop of its own weight into 75 the inoperative position.

6. A bobbin winder including an arm pivoted at one end and having a bobbin spindle and friction wheel upon its free end, a bell crank pivoted upon the arm, and provided 80 with a notch, in one end portion, a stationary stud arranged to be engaged by the notch to hold the arm in operative position and means upon the other end of the bell crank for engagement with the thread when 85 the bobbin is filled to automatically release the bell crank and permit the arm to drop to the inoperative position.

In testimony that I claim the above, I have hereunto subscribed my name.

CHARLES H. GREENWOOD.
